A

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 17,474, dated July 19, 1887.

Application filed June 20, 1887. Serial No. 241,927. Term of patent 3½ years.

To all whom it may concern:

Be it known that I, JULIUS PEGEL, a subject of the Emperor of Germany, residing at Camden, in the county of Camden and State of New Jersey, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a center panel. At each end is shown ornamental ovals. In these ovals and in the cen-

ter of the panel is represented a bunch of 15 "asters," the whole surrounded by an ornamental border, as shown.

What I claim as my invention is—

The design for a rug, consisting of a center panel having at each end ornamental ovals, 20 in which ovals and center of the panel are represented bunches of asters, and the whole surrounded by an ornamental border, as shown.

JULIUS PEGEL.
